The ornamental design for a ship, as shown and described.

DESCRIPTION

1. Ship

1.1 is a front left perspective view of a ship showing my new design;

1.2 is a left side elevational view thereof;

1.3 is a right side elevational view thereof;

1.4 is a front elevational view thereof;

1.5 is a rear elevational view thereof;

1.6 is a top plan view thereof;

1.7 is a left perspective view thereof;

1.8 is a right perspective view thereof; and

1.9 is a rear perspective view thereof.

1. The indication of this design: a Ship; 2. The purpose of this design: a ship for water transportation; 3. The key points of this design: the overall shape; 4. The view that best illustrates the key points of this design: reproduction No. 1.1—perspective view. 5. The bottom surface of this design product can not be seen during normal use and the bottom view is therefore omitted.
